PIPE SMOKER'S SERVING SET

Harold D. Phillips, Delmar, N. Y.

Application August 30, 1934, Serial No. 742,027

1. Claim. (Cl. 131—51)

This invention relates to a device or outfit for serving the needs of pipe smokers.

The pipe smoker has many needs not served nor supplied by the ordinary smoker's outfit or accessories.

For instance, when he is through smoking and desires to remove the unsmoked residue or dottle from his pipe he pounds it on the palm of his hand, usually scattering the moist residue and 10 ash outside the ash tray he is aiming at,—not to mention the soiling of his hand during the operation. Perhaps he will pound the bowl on the edge of the tray or ash receptacle at the risk of nicking the bowl or tipping over the tray and 15 the noise of this operation may disturb other smokers. When he is through smoking or is interrupted and desires to lay the pipe down he is again presented with a problem. If he puts it in the ash tray the outside of the bowl is dirtied 20 with ashes. The chances are that the pipe will rest at such an angle that it will drain into the stem or mouth piece which, of course, is objectionable.

Moreover, with the newer type of pipe having 25 a metal piece or baffle inside the stem the smoker often desires to wipe off the moisture deposited on the metal piece. The question is, where to find a piece of absorbent material to use for this purpose.

30 When the smoker has finished his smoke and desires to clean the stem and mouth piece he is confronted with the job of locating his pipe cleaners and reamer.

This invention has for its salient object to solve 35 the pipe smoker's problems above presented and to provide a smoker's outfit or set having conveniently arranged facilities for supplying the needs of a pipe smoker.

Another object of the invention is to provide 40 an ash tray or receptacle with cushioned means against which a pipe may be tapped to remove the dottle or unsmoked residue.

Another object of the invention is to provide 45 a pipe smoker's serving set with a paper storage receptacle from which paper can be easily withdrawn to clean the pipe.

Another object of the invention is to provide 50 a device of the character described with storage space for pipe cleaners, waste paper, matches, a pipe reamer, etc.

Another object of the invention is to provide 55 a pipe smoker's ash receptacle or tray having a spindle extending upwardly therein for loosening the unsmoked residue or dottle and means for supporting the stem in such a manner that

the pipe will drain into the bowl and not into the stem or mouth piece.

Another object of the invention is to provide 5 a pipe smoker's serving set with a rigid cleaning rod so designed as to remove obstructions in that portion of the stem of the pipe which is an extension of the bowl, and to clean said portion of the stem.

Further objects of the invention will appear 10 from the following specification taken in connection with the drawings which form a part of this application, and in which

Fig. 1 is an elevational view showing a smoker's set or outfit constructed in accordance with 15 the invention;

Fig. 2 is a horizontal sectional elevation through the device shown in Fig. 1 taken substantially on line 2—2 of Fig. 3;

Fig. 3 is a vertical sectional elevation taken substantially on line 3—3 of Fig. 2;

Fig. 4 is a vertical sectional elevation taken substantially on line 4—4 of Fig. 2;

Fig. 5 is a sectional elevation of the ash tray or receptacle showing a pipe supported thereon;

Fig. 6 is a fragmentary sectional elevation 25 showing a modified form of construction of cushioning device or bumper;

Fig. 7 is a top plan view illustrating another embodiment of the invention, the ash receiver being omitted for the sake of clearness;

Fig. 8 is a sectional elevation taken substantially on line 8—8 of Fig. 7, looking in the direction of the arrows; and

Fig. 9 is a sectional elevation through the paper receptacle shown in Fig. 7, this view being 35 taken substantially on line 9—9 of Fig. 7.

The invention briefly described consists of a smoker's set or outfit designed for pipe smokers and having an ash receptacle or tray provided with a central spindle for loosening the unsmoked 40 residue or dottle or for removing stoppages from the bowl end of the stem and furthermore, provided with a bumper or abutment of resilient or cushioning material against which the pipe bowl may be tapped to remove the dottle, and with receptacles for dispensing paper, supporting matches, storing waste paper and storing pipe cleaners, cleaning rods, reamers or other pipe accessories. The units are all mounted on a single base and are accessible to furnish the 45 pipe smoker with all of the necessary appliances.

Further details of the invention will appear 50 from the following description.

In the particular embodiment of the invention 55 illustrated in Figs. 1—6 inclusive, there is shown

a smoker's set or outfit comprising a base 10 having a recess 11 therein for housing a drawer 12 in which may be stored pipe cleaners, reamers or other accessories.

5 There are mounted on the base upwardly extending casings A and B. The casing A has a removable cover 13 and is provided with a ledge 14 and a downwardly inclined shelf 15 spaced below the ledge 14 and providing an opening 16 10 through which sheets S of paper may be withdrawn.

The casing B is provided with an abutment 20 adapted to support a box of matches M and with partitions forming an enclosure of a 15 movable waste paper receptacle R having openings 21 adjacent the upper end in the side walls to facilitate the removal of the receptacle. A pair of hooks 22 are formed on the receptacle for receiving and supporting a pipe reamer of the 20 usual construction. The casing B also has a recess 24 adapted to receive a cleaner rod, or other pipe accessory.

The match supporting abutment, waste paper receptacle and cleaner rod access are carried by 25 a slide or drawer 26 which, as shown in Fig. 4, may be pulled out. Furthermore, access may be had to these parts by removing the cover 27.

Intermediate the housings or casings A and B there is mounted an ash tray or receptacle T 30 which is removably mounted on the base. The tray or receptacle T is preferably provided on a removable bottom 30, as shown in Fig. 5, and a vertically extending spindle 31 is secured to the bottom and extends upwardly slightly beyond the plane of the upper edge 32 or rim of 35 the ash receptacle or tray T. The spindle may be of such diameter as to permit its use in cleaning the bowl end of the pipe stem or, if desired, a second pin 31A may be carried by the base 40 30 to facilitate cleaning the pipe stem.

The upper rim of the receptacle has secured thereto a plurality of segments 33 having pads 34 of resilient or cushioning material, such as cork or rubber. These pads may be secured to the 45 rim in any desired manner as by rivets 35 shown in Fig. 2, or by removable clips 36, as shown in Fig. 6. The rim is also provided with raised portions or pipe rests 40 which may, if desired, be formed of cushioning material and which extend 50 upwardly from the rim of the ash tray or receptacle a sufficient extent to support the pipe in the manner shown in Fig. 5 with the stem and the mouthpiece upwardly inclined so that the moisture will not drain into the stem or mouthpiece when the pipe is inverted on the spindle 31. The upper end of the spindle is preferably wedge shaped and when the smoker desires to loosen 55 and remove the dottle or unsmoked residue from the bowl the pipe will be inverted on the spindle 31 and will be rotated or wobbled on the spindle. After this material has been loosened the user will 60 tap the bowl on one of the resilient bumpers, thus causing the dottle to drop into the receptacle. By providing bumpers of cushioning material nicking of the bowl will be prevented and the tapping operation can be carried out noiselessly.

After the smoker has removed the dottle from 70 the pipe bowl the stem or metal piece therein can be cleaned by paper sheets S obtained from the casing or receptacle A and the soiled paper can be deposited in the waste paper receptacle R. Pipe cleaners can be obtained from the drawer

12 or the cleaner rod can be used to clean the stem.

In Figs. 7-9 inclusive, there is illustrated another embodiment of the invention comprising a base 50 having upright arcuate portions 51 and 5 52, 53 and 54 extending upwardly therefrom. The base also has formed thereon a plurality of radially extending box-like enclosures 55, 56, 57 and 58, these portions being disposed between the arcuate upright portions 51, 52, 53 and 54, as 10 shown in Fig. 7.

As clearly illustrated in the drawings, the box-like portions extend at their inner ends inwardly toward the center of the base beyond the arcuate portions forming ledges on which is supported 15 the ash receiver or ash tray 60, as shown in Fig. 8. The ash receiver conforms in construction to the structure illustrated in the preceding figures of the drawings.

The box-like structures 55 and 57 are enclosed at the top by top portions 61 which may, if desired, have formed thereon or secured thereto upwardly extending abutments 62 for supporting matches. These members 55 and 57 are disposed diametrically opposite each other 25 and pipe cleaners 63 or other pipe accessories may be supported on a base 50 with their ends extending into the box-like receptacles 55 and 57.

The other enclosures 56 and 58 may be used to house receptacles, such as that shown in Fig. 9 at 65. This receptacle has an opening 66 in the top thereof and a slit 67 communicates with the opening and extends to the open end 68 of the receptacle. The receptacle may be used to house paper strips P similar to those shown in Fig. 3, the forward edge of the upper strip being led upwardly through the opening 66.

A similar receptacle is shown in the box-like enclosure 58 and may be used for receiving the waste or discarded paper after it has been used 40 to clean the bowl or stem of the pipe.

In order to hold the receptacles 55 in place the base 50 has formed thereon upwardly extending ridges 70 and 71.

The form of the invention shown in Figs. 7-9 45 inclusive, is attractive in appearance, can be readily and economically manufactured and is adapted in the manner above described to carry out the objects of the invention.

From the foregoing description it will be evident that the pipe smoker's set or outfit described 50 will supply all the needs of the pipe smoker and that he will have at hand all of the accessories and facilities required. It will be understood that various arrangements of the receptacles 55 may suggest themselves and that it is not intended to limit the patent to any specific or definite arrangement of parts.

Furthermore, although one specific embodiment of the invention has been particularly shown and described, it will be understood that 60 the invention is capable of modification and that changes in the construction and in the arrangement of the various cooperating parts may be made without departing from the spirit or scope 65 of the invention, as expressed in the following claim.

What I claim is:

A pipe smoker's serving device comprising an ash tray having a spindle extending upwardly 70 therein and an edge portion so located relative to the top of the spindle that when an inverted pipe bowl is supported on the spindle the stem will be upwardly inclined.

HAROLD D. PHILLIPS.
